(57) CLAIM

I claim the ornamental design for an edible gum for companion animals, as shown and described.

DESCRIPTION

FIG. 1 is a front, top and left side perspective view of an edible gum for companion animals showing my new design; FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.
